[57] CLAIM

The ornamental design for a handle for traffic delineator, as shown.

DESCRIPTION

FIG. 1 is a front perspective view of a handle for traffic delineator embodying our new design and showing the handle on a traffic delineation cylinder for illustrative purposes only and forming no part of the claimed design; FIG. 2 is a close-up perspective view thereof;

FIG. 3 is a top view thereof;

FIG. 4 is a first side view thereof;

FIG. 5 is a second side view thereof;

FIG. 6 is a bottom view thereof;

FIG. 7 is a front perspective view of a second embodiment of a handle for traffic delineator embodying our new design and showing the handle on a traffic delineation cone; FIG. 8 is a close-up perspective view thereof;

FIG. 9 is a top view thereof;

FIG. 10 is a first side view thereof;

FIG. 11 is a second side view thereof; and,

FIG. 12 is a bottom view thereof.
